UNITED STATES PATENT OFFICE.

ISAAC LIBSON, OF BROOKLYN, NEW YORK, ASSIGNOR TO SUNLIGHT REFLECTOR CO., INC., OF BROOKLYN, NEW YORK, A CORPORATION OF NEW YORK.

LIGHTING FIXTURE.

Application filed February 28, 1924. Serial No. 695,791.

To all whom it may concern:

Be it known that I, ISAAC LIBSON, a citizen of the United States of America, residing in the city of New York, borough of Brooklyn, in the county of Kings and State of New York, have invented certain new and useful Improvements in Lighting Fixtures, of which the following is a specification.

10 My invention relates to lighting fixtures, and particularly to a fixture for display window illumination and the like. The object of my invention is to provide a fixture of rugged and serviceable construction 15 which affords suitable distribution and concentration of the light rays.

In the accompanying drawing I have illustrated in broken side elevation a fixture in which my invention is embodied in one 20 form.

The present invention relates to fixtures of the general type used for the illumination of show windows and the like. The present fixture is designed to afford not only a 25 general diffusion of the light from the fixture lamp, but also a spot-light concentration of portion of the light rays upon some particular object in the window to which it is desired to attract particular attention.

30 The fixture is preferably adapted for adjustable installation, and for this purpose is mounted upon an adjustable bracket 1 adapted to be clamped upon a suitable support, and having an associated arm 2 adjustably connected to the bracket 1 so that the fixture body is in effect mounted for universal adjustment with respect to the support. Clamping nuts, such as that indicated 35 at 3, serve to hold the bracket elements in 40 adjusted position.

The body of the fixture comprises a bell shaped canopy 4, to which the bracket arm 2 is attached and to the head of which is secured a lamp socket 5 of conventional type 45 which opens into the bell 4. At the mouth of the bell is secured the reflector.

The reflector comprises a frusto conical shell 6 faced on its inner surface by glass reflector facets 7. This portion of the reflector affords a light dispersing area, and insures the relatively wide dispersion of the light rays for the general illumination of the show window. Associated with the shell 6 is a second frusto conical reflector shell 8,

the inclination or pitch of which with respect to the axis of the fitting is much greater. Glass reflector facets 9 also line the inner face of this shell and serve to concentrate the light rays reflected therefrom, and form in effect a spot-light reflector. 55 60

With fixtures of the present type, it is customary to use gas-filled tungsten lamps as the light source. The filaments 10 of a lamp of this character are located substantially centrally in the bulbous portion 11 of the lamp which is connected by a long neck 12 to the lamp base, (not shown) to which also the supporting stem 13 for the filaments is secured. Lamps of this character become highly heated during use, and it is 65 70 necessary to thoroughly ventilate them to insure longevity. For this purpose the canopy bell 4 is provided with ventilation apertures 14. These are so located with respect to the lamp filament 10, that the direct light 75 from the latter is intercepted by the reflector shell 8, so that no spotty escape of light therethrough into the show window is possible. While the bulbous portion of the lamp, and consequently the filament, is located 80 close to the spot light reflector area 8-9, sufficient space is afforded between the lamp and the central aperture 15 in the reflector 8 to properly ventilate the lamp.

The structural details of the fitting may 85 be varied. I have shown, however, a simple and economical construction and assembly of the parts which is effective and serviceable. At the open end of the fitting I detachably secure to the diffusing reflector 6 90 a ring flange 16, which affords a one-end support for the reflector facets 7. The inwardly projecting margin 17 of the ring flange extends sufficiently beyond the facets to afford means also for supporting a 95 diffusion glass or color screen (not shown), should it be desired to color or diffuse the light emitted. The opposite margin of the shell 6 is cut to afford a series of tongues 18, some of which may be readily bent over the 100 opposite ends of the facets to retain the latter in position.

The shell 8 of the reflector is provided at its central aperture 15 with an in-turned flange 19 which engages at one end the facets 9. The other margin of this shell overlaps and is soldered to the shell 6 beyond the tongues 18, and certain of the latter are 105

bent into engagement with the opposite ends of the facets 9.

The reflector shells 6 and 8 may be soldered together before the facets 7 and 9 are placed in position and the facets thereafter secured by turning down the lugs 18 in opposite directions upon the adjacent ends of the facets as the latter are assembled upon the two reflector shells.

10 The reflector thus assembled may then be secured to the canopy bell 4, the mouth of which is of sufficient diameter to embrace the reflector shell 8 and to sleeve over the shell 6. It is only necessary to insert the reflector into the mouth of the bell and offset the margin 20 of the bell to firmly secure the parts together. The joint is also preferably soldered for additional security.

20 The construction illustrated affords an economical fixture, the metal parts of which may be formed from sheet metal and assembled quickly and strongly. The illumination afforded by the compound reflector secures a highly desirable diffusion and concentration particularly valuable for show window lighting.

25 Various modifications in detail will readily occur to those dealing with the prob-

lem, which do not depart from what I claim as my invention.

30

I claim—

A lighting fixture comprising a canopy bell, a lamp socket arranged at one end of the bell and projecting therefrom and adapted to support a lamp within the bell, 35 in combination with a reflector mounted at the mouth of the bell and comprising a frusto conical diffusion area arranged in extension of the annular wall of the canopy bell, and a central frusto conical spot-light 40 area of greater pitch embraced within the canopy bell but spaced therefrom, the deviation of said spot-light area of the reflector from the wall of the canopy bell progressively increasing toward the axis of the fixture, said spot-light area being centrally apertured to accommodate the neck of an electric lamp inserted therethrough and through the canopy bell into the socket supported at the head of the latter, together 50 with a universally adjustable supporting bracket secured to the canopy bell in the area between the socket and the reflector.

In testimony whereof I have signed my name to this specification.

ISAAC LIESON.
